UNITED STATES PATENT OFFICE.

JOHN LOCK, OF ALAMEDA, CALIFORNIA.

TORPEDO-GUARD FOR SHIPS.

1,285,261.

Specification of Letters Patent. Patented Nov. 19, 1918.

Application filed December 31, 1917. Serial No. 209,696.

To all whom it may concern:

Be it known that I, JOHN LOCK, a citizen of the United States, residing at Alameda, in the county of Alameda and State of California, have invented certain new and useful Improvements in Torpedo-Guards for Ships, of which the following is a specification.

This invention relates to torpedo guards for ships' hulls and has as its object to provide a guard so constructed that the same may be quickly adjusted to position to prevent the hull of the ship being struck by an approaching torpedo, and which guard, when not in use, may be so positioned beside the hull of the ship as to in no way interfere with steering of the ship.

It is one aim of the invention to provide in a device of this class including guards extending substantially the entire length of the hull of the ship at each side thereof, means whereby the guards may be readily adjusted to a raised or lowered position or adjusted in a fore or aft direction so that no matter from what direction the torpedo is fired either or both of the guards may be quickly brought into position to protect that portion of the hull of the ship which is most likely to be damaged by the torpedo.

Another aim of the invention is to so construct the device that while the guard members or plates are sufficiently stout to cause explosion of the torpedo upon striking the same, the said guard members may nevertheless be adjusted and moved into and out of active position readily and with the expenditure of but little power.

The invention also aims to so construct the device that even though the guard members be lowered into the water in guarding position, the ship may still be maneuvered without difficulty if traveling at a relatively low rate of speed.

In the accompanying drawings:

Figure 1 is a side elevation of the guard device embodying the present invention mounted upon the hull of a ship, the device being illustrated with the parts in inactive position;

Fig. 2 is a detail end elevation of one of

the guard members and the supporting booms, the guard member and its supporting booms being shown in full lines in such position that the lower edge of the guard member will be located above the surface 55 of the water and in dotted lines the positions of these parts when the guard member is lowered into active position;

Fig. 3 is a top plan view of the device applied to a ship's hull;

Fig. 4 is a view in elevation looking at the inner side of one of the units of one of the guard members;

Fig. 5 is a group perspective view illustrating the means provided for connecting 65 the corners of the guard units with the outer ends of the supporting booms therefor;

Fig. 6 is a similar view illustrating the means provided for connecting the inner ends of the supporting booms to the ship's 70 hull;

Fig. 7 is a perspective view illustrating a boom rest constituting a part of the device.

In the drawings the numeral 1 indicates in general the hull of a ship and the numerals 2 and 3 indicate, respectively, fore and aft masts which serve a purpose to be presently explained.

One of the guards is located at each side of the hull of the ship and each guard comprises a series of units each in the nature of a guard plate 4 of a suitable metal and sufficiently thick and heavy to cause explosion of a torpedo striking the same. Each of the plates 4 is preferably rectangular in 80 marginal outline, and the outer surface of each plate is preferably smooth. However, each plate is reinforced by means of longitudinally extending substantially semi-circular channel bars 5 which are disposed at 85 their concave sides against the inner face of the plate and are secured at suitable intervals by means of rivets or the like, indicated by the numeral 6. As stated these bars 5 are of channel formation and they are left open at their ends so that water 90 may drain therefrom and thus prevent corrosion of the bars or the portions of the plate against which they are disposed. In forming each of the guards, the required 100

number of units comprising the plates 4, are disposed end to end and are supported in this relation at the outer ends of booms which are connected at their inner ends to 5 the ship's hull. Each of the booms above referred to comprises a tubular arm of a suitable length and the said booms are arranged in pairs one above another and suitably spaced and parallel throughout their 10 length. Into the outer end of each boom 7 there is fitted the shank 8 of a hinge member 9 having an apertured ear 10, the ears of the members 9 which are fitted into the outer ends of the upper booms being turned 15 in a downward direction, as clearly shown in Fig. 5, and those upon the lower booms being turned in an upward direction, also as shown in the said figure. In providing a connection between the members 9 and 20 the corners of the units 4, there are employed swivel members 11 each comprising a plate 12 formed near each end with an opening 13 and upon one side between the openings with an outstanding pivot ear 14 having an opening 15 therein. In assembling these members 11 with the members 9, the ears 14 of the said members 11 are disposed against the ears 10 of the members 9 and pivot bolts 16 are inserted 25 through the openings in the said ears 10 and the opening 15 in the ear 14 thus pivotally connecting the said parts. Secured to the inner face of each unit 4 at each 30 upper and lower corner thereof is a strap 17 terminating at its outer end in a pintle lug 18 and in connecting the swivel members 11 with the said units, the plates 12 of the members are disposed with their 35 openings 13 registering with the openings in the lugs 18, and pivot bolts 19 are fitted through these parts to pivotally connect the same. Thus not only is pivotal connection 40 provided between the outer ends of the upper and lower booms and the upper and lower corners, respectively, of adjacent units of the guard members, but also the meeting ends of the adjacent units are connected 45 with each other so that in effect each guard affords a guard surface extending substantially continuously the entire length of the 50 hull of the ship. It will also be apparent at this point that the booms 7 may be swung upwardly or downwardly, or forwardly or 55 rearwardly due to the substantially universal pivotal connection between their outer ends and the corners of the plates 4, and a similar universal connection is provided between the inner ends of the booms 7 and the 60 ship's hull, as will now be described. Inasmuch as the connections between the inner ends of all of the booms 7 and the ship's hull are of like construction, it will

suffice to specifically describe one of said connections. The connection comprises a 65 plate 20 which is riveted or otherwise secured to the side of the hull and upon the outer face of which plate there is formed a pintle lug 21 having an opening 22 formed vertically therein, the upper face of the lug 70 21 being flat and smooth. The numeral 23 indicates a head provided at its base with a circular bearing portion 24, the under side of which is flat and smoothly finished to rest and turn upon the upper face of the respective pintle lug 21 and formed centrally upon the under side of the base 24 is a depending shank 25 which rotatably fits within the opening 22. At its lower end the shank is formed with a transverse slot 26 80 which, in the assembled relation of the parts, is located immediately below the under side of the lug 21, and a key 27 is provided and is fitted into the slot 26 so as to prevent accidental upward displacement of 85 the shank 25 in the opening 22. The head 23 is formed or provided with an ear 28 having an opening 29 and the inner end of the respective boom 7 is flattened or otherwise formed to provide a pintle ear 30 which is 90 disposed to fit against the ear 28, a pivot bolt 31 being fitted through the openings 29 and an opening 32 formed in the ear 30. It will now be understood that due to the connection provided between the inner ends 95 of the booms 7 and the ship's hull, these booms may have universal movement with relation to the hull. In other words, they may be swung upwardly or downwardly, or may be swung forwardly or rearwardly 100 and also in the various intermediate directions, and this fact together with the fact that a similar universal joint is provided between the outer ends of the booms and the units comprising the guard members, provides for adjustment of the said guard member in any desired direction so that the members may be swung upwardly to inactive 105 position beside the hull of the ship, may be lowered into the water in active position to 110 guard the hull of the ship from torpedoes, may be swung bodily forwardly to particularly afford protection for the bow of the hull, and may be swung rearwardly so as to particularly afford protection for the 115 stern of the hull.

By reference to Fig. 3 of the drawings it will be observed that the foremost ones of the booms are curved along such lines as will adapt these particular booms to lie 120 against the hull at the bow of the ship.

As before stated the guard members may be adjusted to position lying against the hull of the ship when not in use and in order that the booms may be supported while 125 the guard members are in this position, there

is provided, for each boom, a supporting bracket of the form shown in Fig. 7, and indicated in general by the numeral 33. This bracket 33 comprises an attaching plate portion 34 riveted or otherwise secured to the hull of the ship, each bracket being located in a horizontal line with the inner end of the boom which it is to support and being spaced a suitable distance rearwardly 5 from the pivoted inner end of the said boom, as clearly shown in Fig. 3 of the drawings. The supporting member of each bracket is indicated by the numeral 35 and is upwardly and outwardly curved so as to 10 provide a rest designed to receive the boom which the bracket is to support, this supporting portion being preferably reinforced by means of a bracing web 36.

Each of the pivot bolts 16 serves also as 20 the connection for a shackle 37 and connected to each two adjacent shackles 37 throughout the length of the guard member are the ends of a cable 38 which cables constitute bridles serving as a connection between the 25 units of the guard members and an arrangement of raising and lowering cables. Each of the bridle cables 38 is passed slidably through a link 39 and connected to these links are cables 40 which lead to the shackle 30 41 of a pulley block 42. Passed about the pulley of said block is a hoisting cable 43 connected to a similar block 44 upon the mast 2 or the mast 3, as the case may be, it being observed by reference to Fig. 1 of the 35 drawings that the forward units of each guard have their respective cables 40 connected to the block 42 at the forward mast 2 and that the rear units of each guard have their said cables connected to the block 40 41 at the mast 3. The hoisting cables 43 are led to and about steam winches 45 whereby the cables may be quickly taken up or paid out in respectively raising and lowering the guard members. It will be observed by reference to Fig. 1 of the drawings 45 that the guard member illustrated therein is in inactive position, or, in other words, in position beside the hull of the ship, the booms 7 being supported within the brackets 50 33. With the parts in this position, when it is desired to lower the guard members into active position, or in other words, to position extending a suitable distance below the surface of the water, the winches 45 are operated to take up a short length of the cables 43 so as to elevate the outer ends of the booms clear of the supporting brackets 33, whereupon the cables 43 may be paid out so as to permit the guard members to lower 55 to the active position stated. In order that the guard members may be adjusted fore and aft as they are raised and lowered, fore and aft haul cables 46 and 47, respectively,

are connected to the foremost and rearmost shackles 37 and are led respectively forwardly and rearwardly and connected to cleats 48 and 49 located respectively at the bow and stern of the ship. Thus by paying out the cables 47 and hauling in on the cables 46, the booms may be swung forwardly so as to correspondingly move the guard members and thus more especially protect the bow of the ship, or the cables 46 may be paid out and the cables 47 hauled in so as to swing the booms rearwardly and correspondingly adjust the guard members to especially protect the stern of the hull. 65 70 75

Having thus described the invention, what is claimed as new is:

1. A protective device of the class described comprising members for attachment to a ship's hull, booms having universal connections with said members, a guard member supported by the said booms, means for adjusting the parts to vary the position of the guard member, and brackets on the hull having seats extending longitudinally of the hull to be engaged by and retain the booms in inactive position close to the hull. 80

2. A protective device of the class described comprising a guard member consisting of a plurality of units arranged end to end, swivel plates disposed between the ends of adjacent units and having their opposite ends pivotally attached to the ends of the respectively adjacent units, booms connected pivotally at their outer ends with the swivel plates, and means for pivotally connecting the inner ends of the booms with a ship's hull. 90 95 100

3. A protective device of the class described comprising supporting plates to be secured to a ship's hull and provided with pintle lugs, heads having depending shanks pivotally engaging said pintle lugs and provided with outwardly and upwardly extending portions, booms having their inner ends pivotally attached to said outwardly and upwardly extending portions, swivel plates pivoted to the outer ends of the booms, and guard units having their ends pivoted to the opposite ends of the swivel plates. 105 110

4. A protective device of the class described comprising a plurality of units disposed end to end, means for supporting the said units from the hull of a ship for movement in vertical and horizontal planes, bridle cables having their ends connected to the ends of the several units, raising and lowering cables supporting and having movable engagement with the bridle cables, and means upon the ship for operating the said raising and lowering cables. 115 120

5. A protective device of the class described comprising brackets to be secured to the hull of a ship, heads mounted in said

brackets for pivotal movement in horizontal planes, booms pivoted at their inner ends to the upper ends of said heads for movement in vertical planes, swivel plates provided intermediate their ends with lugs pivotally attached to the outer ends of the booms, guard units disposed end to end and

provided at their ends with pintle lugs arranged to overlap the ends of the swivel plates, and means for pivotally attaching 10 the said pintle lugs to the ends of the swivel plates.

In testimony whereof I affix my signature.
JOHN LOCK. [L.s.]
